CONTAINER HAVING SPRING BIASED
SLIDING CLOSUREJoe M. Lyon, Jr., Los Angeles, Calif., assignor, by
mesne assignments, to William E. Wilson, In-
glewood, Calif.

Application July 11, 1947, Serial No. 760,310

3 Claims. (Cl. 220—41)

1

The present invention relates to containers, and has as its primary object the provision of a new and improved container having a spring-biased, sliding lid, which snaps to open position when pressed with sufficient force to overcome a releasable catch, and which is closed by pressing the lid back to its closed position, against the pressure of the spring action.

Another object of the invention is to provide a container which is particularly adapted for use as a cigarette case, and in that capacity serves to preserve the cigarettes from being crushed or broken, or contaminated by dirt, lint, or cosmetics in a pocket or handbag.

A further object of the invention in connection with its use as a cigarette case, is to provide a refillable container which is adapted to receive the standard cigarette pack, and which provides a convenient means for dispensing the cigarettes singly or a few at a time by a one-handed operation, instead of requiring the use of both hands, as has been necessary heretofore.

Still another object of the invention is to provide a container of the type described which is attractive in appearance, compact and durable, and inexpensive to manufacture.

Other objects and advantages of the invention will become apparent to those skilled in the art upon consideration of the following detailed description of the preferred embodiment thereof, reference being had to the accompanying drawings in which:

Figure 1 is a perspective view of a cigarette case embodying the principles of the invention, showing the lid in closed position;

Figure 2 is another view of the same, with the lid shown in open position;

Figure 3 is a sectional view taken along the line 3—3 in Figure 1;

Figure 4 is a similar view, showing the lid in open position;

Figure 5 is an enlarged sectional view taken along the line 5—5 in Figure 3; and

Figure 6 is an enlarged sectional view of a detail, taken along the line 6—6 in Figure 2.

In the drawings, the container of the invention is designated in its entirety by the reference numeral 10 and comprises a generally rectangular case 11, open at the top end and having side walls 13, 14, end walls 15, 16, and a bottom wall 17. The case 10 may be made of any suitable material such as metal, plastic, wood, or the like, and is proportioned to receive a pack 18 of cigarettes, which is inserted into the case through the opening in the top end thereof, after tearing away

2

a portion of the end of the paper wrapping in the usual manner.

Formed on the top edges of the two opposite side walls 13, 14 are parallel ways 20 which provide support for a sliding lid 21. Each of the ways 20 is preferably, although not necessarily, formed as a raised flange extending upwardly from the top edge of its respective side wall and forming a continuation of the inside surface thereof. The top of the flange is rounded, and its outer side is set back from the outside surface of the wall, so that the thickness of the flange is approximately one-half that of the wall. A groove 22 is cut into the outer side of the flange at the base thereof, leaving a web 23. At their front ends, the ways 20 are strengthened and reinforced by inwardly extending buttresses 26 which are formed as extensions of the end wall 15. The rear end portions of the ways 20 are cut away for a short distance back from the walls 16, forming a rearwardly facing shoulder at 24, and leaving a portion of the web 23 standing as a ridge 25 which extends back to the rear wall 16 and along the edge of the latter.

The sliding lid 21 is a flat, rectangular plate having a pair of laterally spaced grooves 30 formed in the underside thereof, which receive the ways 20. Each of the grooves 30 is enlarged in its upper portion to form a generally cylindrical chamber 31, which receives a compression spring 32. The springs 32 are disposed within the spaces formed by cutting out sections of the ways 20, and each of them bears at one end against the shoulder 24 and at the other end against the end 33 of the chamber 31. The springs 32 are compressed when the lid 21 is in the closed position shown in Figures 1 and 3, and press against the lid, urging the same toward the open position shown in Figures 2 and 4. At the front end of the lid 21, the grooves 30 are formed with enlarged recesses 29 which receive the buttresses 26 when the lid is in its closed position.

The center portion of the underside of the lid 21 lying between the grooves 30 is elevated to clear the lip 26, and the outer edges of the lid extend downwardly on the outsides of the ways 20 to meet the top edges of the walls 13, 14; with inwardly turned flanges 34 which extend into the groove 22 to secure the lid 21 to the case 11. A transversely extending lip 35 projects downwardly from the back end of the lid 21 to the top edge of the end wall 16, and this lip is engageable with the lip 26 on the case to limit move-

ment of the lid toward the left or closed position.

The lid 21 is releasably held in its closed position by means of a catch which is formed as a narrow, transversely extending lug 40 projecting downwardly from the underside of the lid at the front end thereof, midway between the grooves 30. The lug 40 is engageable with a lip 41 on the top edge of the front end wall 15 between the buttresses 26, and is adapted to ride up over the said lip and drop into the holding position shown in Figure 3, when the lid is pushed all the way to closed position. A shallow, semi-circular finger recess 42 is formed in the upper portion of the front end wall 15, and this recess leaves the end of the lid 21 projecting or overhanging slightly so that it can be engaged by the finger, as shown in Figure 3, and pushed rearwardly a sufficient distance to force the catch over the lip 41 and thereby release the lid 21 so that the springs 32 are permitted to snap the lid back to open position.

The rearward travel of the lid 21 is limited by a limit stop 45 which is spaced longitudinally from the catch 40 and projects downwardly from the underside of the lid. The limit stop 45 is likewise formed as a narrow, transversely extending lug which is engageable with the lip 26 on the top edge of the rear end wall 16 to stop the lid at the open position shown in Figures 2 and 4. When it is desired to remove an empty pack and replace the same with a full one, the lid 21 can be removed altogether by forcing it rearwardly, causing the lug 45 and catch 40 to ride up over the lip 26. When the case has been filled, the lid 21 is replaced by forcing the same back into position, causing the lugs 40 and 45 to ride up over the lip 26.

The operation of the container is believed to be clear from the foregoing description. The case is opened by pressing with the thumb or finger against the front edge of the lid 21, forcing the catch 40 over its lip 41 and releasing the lid so that it can be snapped back to open position by the springs 32. To close the case, the lid 21 is pressed forwardly by thumb or finger, against the pressure of the springs 32, until the catch 40 is forced up over the lip 41 and dropped down into holding position.

While I have shown and described in considerable detail what I believe to be the preferred form of my invention, it is to be understood that such details are not restrictive of the invention, but that various changes may be made in the shape and arrangement of the several parts without departing from the scope of the broader claims appended hereto.

I claim:

1. A container comprising a case having an opening provided therein, parallel ways extending along two opposite sides of said opening, a lid having a pair of laterally spaced grooves provided in the underside thereof to receive said ways, whereby said lid is slidably supported on said ways for movement between a closed position in which said opening is covered, and an open position wherein said opening is exposed, said ways being cut away at one end to form a shoulder, a pair of compression springs disposed within said grooves, each of said springs bearing at one end against said shoulder and at the other end against the end of said groove so as to urge said lid toward the open position, a catch on said lid engageable with said case for releasably

holding said lid in said closed position against the pressure of said springs, said catch being yieldable under finger pressure applied to said lid in the direction to open the same, thereby releasing said lid and allowing the same to be moved toward the open position by said springs, and limit stop means for stopping said lid at said open position.

2. A container comprising a case having an opening provided therein, parallel ways extending along two opposite sides of said opening, a lid having a pair of laterally spaced grooves provided in the underside thereof to receive said ways, whereby said lid is slidably supported on said ways for movement between a closed position in which said opening is covered, and an open position wherein said opening is exposed, said ways being cut away at one end to form a shoulder, a pair of compression springs disposed within said grooves, each of said springs bearing at one end against said shoulder and at the other end against the end of said groove, a catch projecting downwardly from the underside of said lid and engageable with a lip on said case for releasably holding said lid in said closed position against the pressure of said springs, said catch being yieldable to release said lid when pressure is applied to the latter in the direction to open the same, and a limit stop lug spaced longitudinally from said catch and projecting downwardly from the underside of said lid, said lug being engageable with another lip on said case to stop said lid at said open position.

3. A container comprising a rectangular case open at one end, parallel ways extending along two opposite side edges of said open end, a lid having a pair of laterally spaced grooves provided in the underside thereof to receive said ways, said lid being slidable on said ways between a closed position entirely covering said open end, and an open position partially exposing said open end, a pair of compression springs disposed within said grooves, each of said springs bearing at one end against the end of its respective groove, and at the other end against the end of said way, a recess formed in one end wall of said case adjacent the edge of said lid, a catch projecting downwardly from the underside of said lid and engageable with a lip on said one end wall of the case for releasably holding said lid in said closed position against the pressure of said springs, said catch being yieldable to release said lid when pressure is applied to the latter in the direction to open the same, a limit stop lug spaced longitudinally from said catch and projecting downwardly from the underside of said lid, said lug being engageable with a lip on the other end wall of said case to stop said lid at said open position.
